COMBINED DOORKNOB AND ESCUTCHEON

Gerard N. Stelma, 1755 Millbrook SE.,
Grand Rapids, Mich.

Filed Mar. 25, 1960, Ser. No. 59,867

Term of patent 14 years

(Cl. D50—6)

FIG. 2

FIG. 1

FIG. 1 is a front elevational view of a combined door knob and escutcheon showing my new design;

FIG. 2 is a side elevational view thereof;

FIG. 3 is a perspective view thereof.

I claim:

The ornamental design for a combined doorknob and escutcheon, as shown.
